UNITED STATES PATENT OFFICE.

FRANCIS K. FASSETT, OF DAYTON, OHIO, ASSIGNOR TO EVANS & HOWARD FIRE BRICK COMPANY, OF ST. LOUIS, MISSOURI, A CORPORATION.

HOLLOW TILE.

1,095,147.

Specification of Letters Patent. Patented Apr. 28, 1914.

Application filed June 30, 1913. Serial No. 776,499.

To all whom it may concern:

Be it known that I, FRANCIS K. FASSETT, a citizen of the United States, residing at Dayton, in the county of Montgomery and State of Ohio, have invented a new and useful Hollow Tile, of which the following is a specification.

My invention relates more particularly to hollow tiles for building sanitary sewers. 10 While tiles for this purpose are not new, those made in the past have had certain serious faults along with some decided advantages, and one of the objects of this invention is to enable the construction of tiles 15 for sewers which embody these advantages while eliminating the faults of the older forms.

Another object is to provide an interlock at the end joints of the several tiles whereby 20 the sewer is much strengthened.

Other advantages resulting from my structure will be pointed out anon.

In the accompanying drawing Figure 1 is a cross section through a portion of a cylindrical sewer built with my tiles, the section being on line 1—1, Fig. 2; Fig. 2 shows two tiles abutting end on; Fig. 3 is a perspective view of a tile, and Figs. 4, 5 and 6 show cement joints between adjacent blocks, to 30 illustrate how sewers of different diameters may be built with tiles of the same size.

Similar numerals refer to similar parts throughout the several views.

Each tile comprises a top 10, bottom 11, 35 side or radial walls 12 and 13, tangential web 14 and vertical or radial web 15. The top, bottom, and web 14 are the same length, and the top and bottom are in perpendicular alinement with each other; i. e., their 40 ends are even, while the web is longitudinally displaced so as to extend beyond the top and bottom at one end. The side walls reach to this extended end, sloping from approximately where they join the top to 45 the end of the web. On a line flush with the lower surface of the web 14 the side walls are cut away, back to a point flush with the end of the bottom. The web 15 continues out to the end of web 14 on a slope 50 parallel with that of the side walls, the sloping ends of the three radial members being,

in fact, not only parallel but in alinement, thereby facilitating manufacturing the tiles. The web 15 is also cut away below the web 14 in the same manner as the side walls. 55 Notches are cut in the opposite ends of the radial members which are complementary to the sloping extensions, except that the lower parts of the notches extend below the lower surface of the web 14. When similar 60 tiles are placed end to end their tops, bottoms and webs abut; and since the webs 14 are longitudinally displaced the extending end of the web of one tile enters into the other tile and overlaps its bottom. There 65 being a space between the web 14 and the bottom of each tile, there will be a corresponding space between the overlapping portions of abutting tiles. The projecting portions of the radial members fill the complementary notches in the end of the abutting tile, except below the overlapping web 14, where, because of the notches being larger than the projections, spaces 16 are 70 formed, these spaces being in line with and 75 practically continuations of the space between the overlapping portions of the tiles.

Joints between the radial walls of contiguous tiles are made with mortar or cement, and in order to increase the strength 80 of these joints the walls 12 have curved projections or tongues, and walls 13 have curved grooves which are complementary to these tongues, both being cylindrical and formed on the same radius. The tiles being seg- 85 mental in cross section a given number will be required to make a circle. Supposing they are made of such size that it requires eleven tiles to construct a thirty-three inch sewer, it has been found that ten of the same 90 size blocks will complete a thirty-inch circle while twelve will make a thirty-six-inch circle. The circular tongue and groove construction of the sides of the blocks permits the necessary adjustment between contiguous tiles. Figs. 4, 5 and 6 show the effect 95 of this adjustment upon the mortar contained in the joint, Fig. 4 showing the form of the joint where tiles are used in a sewer smaller than they are made for, Fig. 5 showing the joint where the size of the sewer corresponds with the radius of the tiles and 100

Fig. 6 showing the form of the joint where the sewer is larger than the tiles are exactly intended for.

In laying up the tiles it is customary to 5 "break joints"; that is, each longitudinal row of tiles is so placed that its end joints terminate opposite the middle of tiles on each side of it. In Fig. 1 the tiles are arranged in this manner. In building with 10 these tiles, mortar is placed between the overlapping portions of the tiles, which, connecting with the mortar in the radial joints through the spaces 16, as shown in Fig. 1, makes as perfect a seal at the ends 15 of the tiles as that between their radial walls. Reference to Fig. 2 will show that, because of the sloping parts of the notches of one tile being abutted by the sloping extensions of the next tile, the mortar joint 20 between the ends of abutting tiles cannot be subjected to tensile strain. In other words, each tile is prevented from up or down movement with reference to its neighbor by means other than adhesion of the mortar. 25 It will therefore be seen that the end joints are capable of standing very great strain without sustaining injury.

In addition to making a perfect seal of 30 very great mechanical strength between ends of my tiles, their form affords opportunity to utilize the same sewer for both sanitary and surface drainage, the latter being carried off between the outer walls 10 and webs 14. As the end seals are made by mortar 35 compressed between the webs 14 and the inner walls 11, the outer spaces of the tiles are kept entirely free from mortar and no effort is required to keep them thus clear.

Minor changes might be made in the form 40 of this tile without departing from the substance or exceeding the scope of the appended claims.

What I claim is as follows:

1. A hollow tile having a top and bottom 45 wall and an intermediate web, all of the same length and united by two side walls, the top and bottom being in perpendicular alinement with each other, with the web being longitudinally displaced with reference 50 to them so it will overlap the bottom of a similar tile when the two tiles are abutted end on, said longitudinal displacement of the web allowing room at the other end for the overlapping end of a similar tile when 55 the two tiles are abutted end on.

2. A hollow tile having a top and bottom wall and an intermediate web, all of the same length and united by two side walls, the top and bottom being in perpendicular alinement with each other, with the web being longitudinally displaced with reference 60 to them so it will overlap the bottom of a similar tile when the two tiles are abutted end on, said longitudinal displacement of

the web allowing room at the other end for 65 the overlapping end of a similar tile when the two tiles are abutted end on, a portion of each side wall being removed at this end to form spaces 16.

3. A hollow tile having a top and bottom 70 wall and an intermediate web, all of the same length and united by two side walls, the top and bottom being in perpendicular alinement with each other, with the web being longitudinally displaced with reference 75 to them so it will overlap the bottom of a similar tile when the two tiles are abutted end on, said longitudinal displacement of the web allowing room at the other end for the overlapping end of a similar tile when 80 the two tiles are abutted end on, and means incorporated in the side walls whereby the distance between the bottom and the overlapping end of an abutting tile is prevented from exceeding the distance from said bottom to its own web.

4. A hollow tile having a top and bottom 85 wall and an intermediate web, all of the same length and united by two side walls, the top and bottom being in perpendicular 90 alinement with each other while the web is longitudinally displaced so as to extend beyond them at one end, the side walls reaching to said end, sloping from approximately where they join the top to the end of the web, but being cut away on a line with the lower surface of the web back to the bottom, the opposite ends of the side walls having notches complementary to the extending ends, except that the lower portions of 95 the notches extend lower down.

5. A hollow tile of segmental cross section having two concentric walls and an intermediate tangential web, all of the same length and united by radial walls, the concentric walls being in alinement with each other while the web is longitudinally displaced so as to extend beyond them at one end, the radial walls reaching to said end, sloping from approximately where they join the outer wall to the end of the web, but being cut away on a line with the inner surface of the web back to the end of the inner wall, the opposite ends of the radial walls having notches complementary to the extending ends, except that the lower portions of the notches extend lower down.

6. A hollow tile of segmental cross section having two concentric walls and an intermediate tangential web, all of the same length and united by radial walls and a radial web, the concentric walls being in alinement with each other while the tangential web is longitudinally displaced so as to extend beyond them at one end, the radial walls and web reaching to said end, the former sloping from where they join the outer wall to the end of the tangential web,

the radial web also sloping to meet the end of the tangential web, its slope being in line and parallel with those of the radial walls to a line perpendicular with the end of the outer wall, from which point the end of the web is flush with and perpendicular to said outer wall, the opposite ends of the radial walls and web having notches complemen-

tary to the extending ends, except that the lower portions of the notches extend lower down.
